KNITTING APPARATUS

Raymond Kretser, New York, N. Y.

Application January 27, 1941, Serial No. 376,061

15 Claims. (Cl. 66—135)

The present invention relates to knitting apparatus and more particularly to apparatus for practicing the knitting methods and for producing the knitted fabrics described and claimed in my co-pending application filed July 31st, 1940, Serial No. 348,754.

In my said application I described a method whereby a multiplicity of individual yarns, a number far greater than heretofore possible, may be incorporated, by knitting, into a knitted fabric in which each stitch consists of yarn from but a single yarn feed and in which several different forms of stitches are formed, to thereby provide knitted fabrics of greater variety and complexity of color and design than heretofore possible and which are of light weight and of relatively reduced elasticity in all directions.

The method therein described, broadly stated, consists in eliminating certain of the needles on a machine from knitting course-wise stitches, in the conventional manner, in a particular course, and in supplying to each of such eliminated needles an individual yarn to be knitted by it in stitches that are connected walewise of the knitted fabric; the course-wise and wale-wise stitches being floated across one another and the floats interlocked with the stitches.

In my said application I have also explained that this new method of knitting may be combined with the methods for producing variety in color and design in course-wise knitting as heretofore practiced; that it may be practiced in addition to other methods and not as a substitute for them.

It is the object of the present invention to provide knitting apparatus of a type which has long been sought in the art but heretofore never attained, namely, a circular knitting machine that could knit vertically or wale-wise of the fabric, as well as horizontally or course-wise of the fabric and which could utilize individual yarns for each individual needle on the cylinder.

It is the object of the present invention to teach the combination and arrangement of the elements and parts of a knitting machine to enable the elimination of certain needles from course-wise knitting, in a particular course, and to enable the knitting upon said eliminated needles of individual yarns in a series of wale-wise connected loop stitches which are incorporated in the fabric by interlocking with the float of the coursewise stitches knitted upon the other needles.

It is also an object of the present invention to provide convenient and practical supporting

means for the great multiplicity of individual yarn spools necessary to supply each of the multiplicity of needles eliminated from course-wise knitting in the several courses formed during a revolution of the apparatus, which may equal the entire number of needles on the cylinder, with an individual yarn, and means to guide the numerous yarns in spaced, readily separable and easily accessible arrangement, for facility in threading, repairing breaks, and the like.

While, as I have explained in my said co-pending application, many types of knitting machines may be adapted and arranged for the practice of the knitting methods described, I have chosen, in the accompanying drawings, to illustrate the principle and practice of the invention by a conventional, well known knitting apparatus of the stationary, cylindrical needle-bed type, which is provided with needle raising and yarn guiding mechanism and yarn feed stations movable relative to the needle bed.

As such apparatus is well known to and the operative linkage and arrangement of its parts well understood by those skilled in the art, I have illustrated such knitting apparatus in the accompanying drawings, except for such new and novel parts which constitute part of the present invention, in a more or less diagrammatic or schematic manner, not having thought it necessary to show details of the structure of the various standard parts or of their specific operative linkage to one another or with the pattern controlling and driving mechanism of the apparatus.

35 In the drawings:

Fig. 1 is a fragmentary, schematic top plan view of knitting apparatus of the present invention showing the relative arrangement and combination of the needle cylinder, needle actuating cams and pattern wheels, stiper arms, wrap fingers and the two sets of yarn feeds;

Fig. 2 is a schematic view of the fragmentary portion of the apparatus illustrated in Fig. 1, laid out flat to illustrate the several types of knitting done on the apparatus;

Fig. 3 is a fragmentary vertical sectional view through the apparatus of the present invention, showing, more or less diagrammatically, the relative arrangement of the operative parts and the structure and relative arrangement of the spool rack from which yarn is supplied to the wrap fingers.

Fig. 4 is a fragmentary side elevational view of one of the spool supporting elements of the rack showing the relative arrangement of the

spool supporting pins and of the tensioning members;

Fig. 5 is a fragmentary front view of the portion of a spool supporting element shown in Fig. 4 of the drawings;

Fig. 6 is a fragmentary plan view of a portion of the lower plate of the rack illustrating the arrangement of guiding apparatus which is similar to the arrangement of the lower yarn guiding plate of the rack.

Generally stated, the invention consists in providing a knitting machine of the character described with a plurality of groups of cams or other means for raising needles to latch clearing position, such as pattern wheels, arranging the cams of each set, each to move selected needles on the cylinder to latch clearing position, with all of the cams of each group complementing one another and combining to raise all of the needles on the cylinder to latch clearing position; the cams and cylinder being arranged to be movable relative one another; providing mechanism, such as stripers, movable synchronously with the cams, for guiding yarn to the needles raised to latch clearing position by certain of said cams, providing relatively stationary, individual yarn guiding and feeding means, such as wrap fingers, for each needle raised to latch clearing position by the others of the said cams; and providing cam means for synchronizing the movement of the guiding and feeding mechanism with the latch clearing movement of their respective needles and providing means for supplying, leading and spacing individual yarns for each of the guiding and wrapping fingers.

The last named means includes a plurality of spaced spool supporting members pyramidally disposed above the needle cylinder, and a guide plate having an individual guiding aperture for each yarn, disposed in convenient position relative the wrap fingers, such as at approximately the level of such fingers.

Referring more specifically to the apparatus of the present invention and with reference to the accompanying drawings illustrating the same, such apparatus includes a needle bed, such as the stationary needle cylinder 52, which may be of conventional design, on which may be conventionally mounted needles 50, preferably of uniform, conventional, standard type throughout, and having the conventional latches 51.

A rotary table, generally designated as 53, and comprising multiple rings in unitary structure, of the conventional type, is arranged about the needle cylinder 52. Such table may consist of a lower, or cam ring 13, which is connected with the drive of the apparatus (not shown) on which may be mounted the cams for raising and lowering the needles; an intermediate ring 14, on which may be mounted yarn guides, such as stripers, associated with knives, latch openers and other conventional devices not of importance in connection with the present invention; and an uppermost ring 15, on the upper face of which may be mounted the bobbin rack frame supporting posts 16, and on the underside of which may be mounted wrap finger actuating cams 27.

The posts 16 may carry, at their bases, the conventional gears 20, which mesh on one side, with a stationary gear ring 21 and on the inside of the apparatus with a second stationary gear ring 22 lying above the opening of the needle cylinder 52 and serve to steady the rotary table and the structure supported thereon.

The lower ring 13 carries a plurality of sets or

groups of cams 56 and intermediate cams adapted to raise all of the needles 50 on the cylinder 52 to tucking position, cams above cams 56 lowering the needles to welting position, and each associated with a pattern wheel; such as A, B or C, each provided with jacks 23, selectively arranged to move selected needles raised by the associated cam 56 to latch clearing or knitting position. The jacks 23 of the several pattern wheels are

10 so set that the several pattern wheels complement one another to raise all of the needles on the cylinder to latch clearing position, without any needle being raised by more than one wheel during any revolution of a set of wheels about the cylinder 52. In this manner each set of cams 56 and associated pattern wheels produces one knitted course of single yarn stitches during each revolution thereof about the cylinder 52.

The number of pattern wheels in each set may 20 be two or more, as may be desired. In the illustrative embodiment of the drawings, the pattern wheels and associated cams are employed in sets of three, and the wheels are designated in the order in which they operate, as A, B and C, respectively.

Any desired number of sets or groups of pattern wheels and cams may be used within limitations of space, such number of sets determining the number of courses knitted during each complete revolution of ring 13 about the cylinder 52. Thus, for example, in my aforementioned pending application, the number of sets of pattern wheels A, B and C, mounted on ring 13, as evidenced by the number of courses knitted during each revolution, is four.

One or more pattern wheels, such as A and B, in the drawings, are each associated with a movable yarn guide, to feed a yarn to all of the needles selectively raised by its associated wheel to latch clearing position. This guiding means may 40 consist of stripers, such as the stripers A' and B', each of which may have a plurality of arms 55 such as the four illustrated.

These stripers may be of conventional type and 45 conventionally set up on intermediate ring 14, to be operated for change of yarn, in accordance with a predetermined pattern or design, by conventional cams, not thought necessary to be shown. They may be associated with conventional knives, also not thought necessary to be shown, as these do not constitute part of the present invention.

Yarn for each of the stripers is, preferably, supplied from an associated group of bobbins 57 fitted 55 on bobbin supports 25 arranged on the rack 26 which is supported on posts 16 mounted on the upper ring 15. Each group of bobbins, designated diagrammatically, by way of illustration, as A¹ and B¹, supplies the yarn for the arms of stripers A' and B', respectively.

It will be readily apparent that the bobbins move synchronously with the stripers A' and B' and with the pattern wheels A and B, and that the yarns fed by stripers A' and B', one at a time, such as yarns a and b, will be knitted by the needles raised by pattern wheels A and B, respectively, in alternate series of course-wise connected stitches of the conventional jersey type, the connecting portions between groups of stitches from the yarns fed from the same stiper being floated across the backs of the stitches formed from the yarn fed by the other stiper, in a manner which will be quite plain to those skilled in the art.

In order to form a compact and economical

fabric which is of a minimum elasticity, the cam 56 associated with one of the pattern wheels, such as B, which may be set to raise selected needles to latch clearing position at relatively great space intervals, necessarily forming long floats between successive series of stitches formed by it, may be set to hold in tucking position those needles not raised by its associated pattern wheel to latch clearing, after they have been passed by the wheel, so as to hold the floats on the needles not knitted by the wheel, to retain the floats closely against the fabric, thereby preventing sagging and utilizing a minimum of yarn in the floats, to form a compact, reinforced fabric of maximum economy and of minimum elasticity.

The other stripe fed pattern wheel, such as A, may be associated with a raising cam 56 which raises the needles to the tuck position. A conventional split type cam 56', such as is disclosed in my United States Patent No. 1,970,238, will lower to welt position the needles not knitted by the wheel A, in the manner schematically illustrated in Fig. 2 of the drawings.

The other pattern wheels, such as C, are exclusively associated with different yarn guiding mechanism. Such mechanism consists of individual yarn guides and feeds which are stationary relative the cylinder and which will lead and feed an individual yarn to each needle raised by the jacks of the wheel to latch clearing position. Such yarn guiding and feeding means may consist of wrap fingers 60 of the conventional type, such as those having the diagonally turned end 59 provided with guide eyes 58. These wrap fingers may be conventionally pivotally mounted on a wrap finger cylinder, suitably positioned directly above the opening in the needle cylinder 52. The apparatus may be set up with an individual finger 60 for each of the needles 50 on the cylinder.

A wrap finger actuating cam 27 is mounted preferably, on the underside of the upper ring 15 above the wheel C, in position to move all the wrap fingers as they are approached by the active portion of the pattern wheel, namely, the point contacting the needle cylinder 52 immediately below, to wrapping position, so that if any jack is arranged at a particular point on the wheel C, the wrap fingers 60, directly above the point where such jacks contact the cylinder will be moved to wrapping position, and will meet the needles raised to latch clearing by said jacks and wrap yarn about them. And when the wrapped needles are lowered by the associated cam to cast-off position, a loop stitch will be formed on each of such needles, as they are lowered to the sinker line.

This operation is best illustrated in Fig. 2 of the drawings, which shows individual yarns, d and e, wrapped around needles, d' and e', raised to latch clearing by jacks 28 of wheel C, by wrap fingers d² and e². It will be understood that the wrap finger cams are so arranged that the wrap fingers are released by them, to return to their initial normal position before their respective needles are lowered from latch clearing position, to allow the finger end 59 to pass its respective needle on one side, under pressure of the cam and to return to normal position by passing on the other side of the needle, when released by the cam, before the needle is lowered from latch clearing position, so that the yarn is wiped about both sides of the needle.

It will be apparent that each needle raised to latch clearing position by wheel C, such as

needles d' and e', will knit an individual yarn, such as d and e, exclusively, not knitted by any other needle on the machine, and that during any knitted course, such needle will knit no other yarn, so that each stitch formed by needles d' and e' will be of but a single yarn (unless a double yarn is fed by fingers d² and e²), and the stitches formed from such individual yarns as d and e, will be loop stitches continuous and connected to one another longitudinally or wale-wise of the fabric. Such yarns as d and e will have no connection with the other yarns in the fabric by plaiting of stitches, or in the manner in which yarns a and b are connected, but will 10 be integrated into the fabric by locking the coursewise floats of yarns a and b between the loop portions of their own stitches and the floats connecting such loop portions of one stitch to the next succeeding stitch formed from the same 15 yarn in a contiguous knitted course. It will be understood that the tucking of the floats of yarn b, as explained above, will insure the interlocking of even the long floats formed thereby in the loop stitches.

20 It will be remembered, that several sets or groups of pattern wheels A, B, and C are arranged on ring 13, and that each group has at least one pattern wheel C which knits yarn from stationary guides. And it may here be stated 25 that each wheel C of the several sets may be arranged to cause to knit needles partly or wholly different from those caused to knit by wheels C of the other sets. As each wheel C may operate a large number of needles, it will be clear that a 30 great number of needles, which may equal all of the needles on the machine, may be arranged to knit, in one course or another, individual yarns, 35 in the manner explained, during a single course about the cylinder 52.

40 To make possible the provision of a safe number of "ends" or individual yarns to supply each of such great multiplicity of needles on the cylinder that may be knitted by pattern wheels C, I have devised a new and novel stationary spool 45 rack for the knitting apparatus. In this rack, I incorporate the requisite number of spool supporting members, each provided with a new and novel compact yarn guiding and tensioning member. These tensioning guides are so arranged 50 as to dispose the individual yarns guided by them in laterally spaced relation so that they may be readily distinguished from one another and easily handled and manipulated for connection with the individual wrap fingers. For that purpose, 55 the guides, which may preferably be of uniform size, are arranged in vertical rows, in spaced relation to one another, with the rows inclined at an angle, so that the vertical spacing of the tensioning guides will also provide lateral spacing from one another for the yarns guided by them.

One convenient and practical embodiment of 60 a rack which provides the foregoing advantages of compactness and proper disposition of the yarns relative one another, is illustrated in the drawings, in which the rack comprises an upright post 70 suitably supported in the hub of the inner ring 22.

A pair of spaced, circular or disk members or 70 plates may be fixed on the post 70, one, 71, of a relatively lesser diameter, on the upper end of the post 70 and another, 72, of a relatively greater diameter on the lower portion of the post 70.

A plurality of rods or bars 73 are arranged 75 preferably in a circle, intermediate the plates, 71

and 72 and secured to such plates adjacent their circumference by feet 74. As plate 71 is of lesser diameter than plate 72 the posts 70 will, as a result, be inclined to the vertical, to form a hollow, open-faced frusto-conical structure. The rods, 13 are spaced from one another just sufficiently to permit arrangement between them of a spool supporting member and of a yarn guiding and tensioning member.

The spool supporting means may comprise a plurality of pins 75 secured by one of their ends to one side of the bar 73 in spaced preferably parallel relation to one another and extending outwardly of the rack structure at an angle to the bar, 73 and to the vertical. It will be readily apparent that, in such position, each pin will be able to support a yarn spool 76 (D and E in Fig. 1). And it will be also clearly realized that as these spools supply yarn knitted vertically of the fabric and not circumferentially, the supply of yarn carried by them need not be as great as that usually carried on a bobbin of the conventional type and that consequently these spools may be of small diameter, permitting a close spacing of pins 75 and, consequently, permitting the arrangement of a large number of pins 75 on each bar 73.

The tensioning guides, generally designated as 17, are preferably arranged to the other side of the bar 73 from the pin 75 with which they are associated. Such tensioning members preferably comprise an arm 78 having an offset end 79 by which it is secured to the bar 73 preferably in position to maintain the arm 78 parallel to the bar 73 and to the pins 75. The free end 80 of the arm 78 is forked, with each of the prongs provided with a yarn guiding aperture 81.

In order to provide sufficient tensioning on the yarn guided in the apertures 81 in the small space between bars 73 I have devised tensioning means which operates at right angles to the direction of movement of the yarn rather than the customary tensioning means which act in the line of movement of the yarn. For that purpose, I provide a spring wire 82 having a coiled end 83 which fits over and is secured to or by a pin or screw 84 set into the arm 78. The spring wire 82 is so arranged that its end, having an eyelet 85 is disposed opposite the space between the prongs of the forked end 80 of the arm 78 and is urged away therefrom by the coil 83 at the base thereof.

In operation, yarn from a spool 76 mounted on a pin 75 is passed through one eyelet 81 of an associated tensioning guide 17 then through the eyelet 85 at the end of the spring wire 82 and then through the second eyelet 81 of the guide 17. It will be apparent that the coil 83 at the end of the spring 82 will tend to force the eyelet 85 away from the forked end 80 thus exerting tension against the yarn passing therethrough.

To permit leading of the yarns from the rack to the wrap fingers, the lower plate 72 is provided with apertures 86 which may have suitable eyelets set therein, one for each of the pins 75 on the rack. These apertures are preferably so arranged as to provide a maximum of space between all the yarns passing and guided therethrough. This maximum spacing may best be obtained by arranging the apertures 86 in a plurality of rows preferably one for each of the bars 73 with each row arranged at an angle to a radius of the plate.

For greater ease and convenience in handling the yarn, a guide plate 88 may be provided at 75

substantially the level of the wrap finger ring. This plate 88 may be supported in any suitable manner, as by brackets 89 depending from the web of the inner ring 22. This plate 88 may also be provided with yarn guiding and spacing apertures 90 similar in form and arrangement to the apertures of the plate 72. For greater convenience, however, and for greater ease in threading the wrap fingers by increasing the spacing and accessibility of the yarns, the plate 88 may be of a downwardly tapering, conical or frusto-conical shape to provide a greater area along which the apertures 90 may be distributed, thus enable the provision of a greater space between the individual apertures.

This completes a description of the apparatus of the present invention. It will be clearly seen from this description that the present invention, by the novel, though relatively simple arrangement of standard parts, together with the new and novel stationary spool rack which supplies an individual yarn or end for each needle on the cylinder make possible the production of a knitted fabric in which, if desired, every stitch may be in a vertically continuous line of stitches or, if desired, may comprise a mixture of course-wise and vertical stitches.

It will also be clearly apparent that the present invention provides a machine in which vertical knitting may be combined with the more complex type of course-wise knitting as described in my aforementioned co-pending application and which may even be combined with racking arrangement for the wrap finger ring to cause the wrap fingers to wrap different needles, in different courses, in a racking staggered arrangement.

What I claim is:

1. Knitting apparatus of the character described, comprising in combination, a needle bed having needles thereon, cam means for raising selected needles to latch clearing position, said cam means and said needle bed being movable relative to one another, yarn guiding means associated with said cam means and stationary relative thereto to feed yarn exclusively to the selected needles raised by said cam means, cam means for raising other selected needles to latch clearing position arranged in fixed relation relative the first named cam means, yarn guiding means associated with the said last named cam means, for feeding, exclusively, an individual yarn to each of the selected needles raised by the said last named cam means, said individual yarn guides being stationary relative to the said first named cam means and a spool rack and associated series of yarn spacing and guiding means stationary relative to the said needle cylinder and each series of yarn guiding means lying in a straight row which is at a relatively small angle to an intersecting radius of the needle cylinder.

2. Knitting apparatus of the character described, comprising, in combination, a needle cylinder having needles arranged thereon, a plurality of cam means, each including a pattern wheel and, each arranged to raise selected needles not raised by the others to latch clearing position, one or more of said cam means provided, exclusively, with yarn guiding means stationary relative thereto for feeding yarn to all of the needles selectively raised thereby and one or more of said cam means having, exclusively, yarn guides movable relative thereto for feeding exclusively, an individual yarn to each of the needles selectively raised thereby, a bobbin rack

stationary relative said first named yarn guiding means and a spool rack stationary relative said second named yarn guiding means, said spool rack including a plurality of spool supporting members arranged in frusto-conical formation above the said cylinder and a yarn guiding and spacing plate arranged intermediate said spool supporting members and said needle cylinder.

3. Knitting apparatus of the character described comprising, in combination, stationary 10 needle cylinder having needles arranged thereon, a rotary table mounted around said cylinder, a plurality of sets of needles raising cams mounted on said table, each of said sets including two or more cams each adapted to raise all of the 15 needles on the machine to tucking position, each of said cams associated with a pattern wheel having jacks arranged to raise exclusively, selected of the needles to latch clearing position, during a revolution about the cylinder, one or 20 more of said cams in each set each associated exclusively with yarn guiding means mounted on the said table and adapted to feed a yarn to all of the needles raised to latch clearing position by its associated pattern wheel, a wrap finger 25 ring mounted in operative position over said needle cylinder and having a plurality of wrap fingers pivoted thereon, the other of said cams associated with a wrap finger moving cam mounted on the table, to move all of the wrap 30 fingers to wrapping position at a point opposite the point of contact between its pattern wheel and the needle cylinder, and a yarn spool rack mounted above said wrap finger ring, said rack including a plurality of upstanding, inclined 35 bars, each bar having a plurality of yarn spool supporting pins fixed thereon in spaced relation and at an angle to the bar and to the horizontal, and a yarn spacing and guiding plate arranged at an angle to the horizontal, said plate having a plurality of yarn guiding apertures.

4. Knitting apparatus of the character described comprising, in combination, a stationary needle cylinder having needles arranged thereon, a rotary table mounted around said cylinder, a plurality of sets of needle raising cams mounted on said table, each of said sets including two or more cams adapted to raise all of the needles on the machine to tucking position, each of said cams associated with a pattern wheel having 40 jacks arranged to raise, exclusively, selected of the needles to latch clearing position, during revolution about the cylinder, one or more of said cams in each set each associated exclusively with yarn guiding means mounted on the said table and adapted to feed a yarn to all of the needles raised to latch clearing position by its associated pattern wheel, a wrap finger ring mounted in operative position over said needle cylinder and having a plurality of wrap fingers pivoted thereon, the other of said cams being associated with a wrap finger moving cam mounted on the table to move all of the wrap fingers to wrapping position at a point opposite the point of contact between its pattern wheel and the needle cylinder, and a yarn spool rack mounted above said wrap finger ring, said rack including a plurality of upstanding inclined bars, each bar having a plurality of yarn spool supporting pins fixed thereon in spaced relation and at an angle to the bar and to the horizontal, and a yarn guiding plate arranged at an angle to the horizontal and having a plurality of yarn guiding apertures arranged in rows set at an angle to the radii of the said wrap finger ring.

5. Knitting apparatus of the character described, comprising in combination a stationary needle cylinder having needles arranged thereon, a rotary table mounted around said cylinder, a plurality of sets of needle raising cams mounted on said table, each of said sets including two or more cams adapted to raise all of the needles on the machine to tucking position, each of said cams associated with a pattern wheel having jacks arranged to raise, exclusively, selected of the needles to latch clearing position during revolution about the cylinder, at least one of said cams formed to continue the needles not raised by its pattern wheel in tucking position, one or more of said cams in each set each associated exclusively with yarn guiding means mounted on the said table and adapted to feed a yarn to all of the needles raised to latch clearing position by its associated cam, a wrap finger mounted in operative position over said needle cylinder and having a plurality of wrap fingers pivoted thereon, the other of said cams being associated with a wrap finger moving cam mounted on the table to move all of the wrap fingers to wrapping position at a point opposite the point of contact between its pattern wheel of the needle cylinder, and a yarn spool rack mounted above said wrap finger ring, said rack including a plurality of upstanding inclined bars, each bar having a plurality of yarn spools supporting pins fixed thereon in spaced relation and at an angle to the bar and to the horizontal, and a yarn guiding plate arranged adjacent the said wrap finger ring at an angle to the horizontal and having a plurality of yarn guiding apertures arranged in rows set at an angle to the radii of the said wrap finger ring.

6. A rack for a knitting machine or the like, for supporting a multiplicity of yarn spools, including a plurality of circularly arranged, diagonally disposed bars, a plurality of spool supporting pins fixed on each of said bars, parallel to and spaced apart from one another and at an angle to the horizontal, a yarn spacing and guiding member below said bars, said member having a plurality of spaced yarn guiding apertures therein, said apertures being arranged in rows disposed at an angle to a radius of the circle formed by the said bars.

7. A rack for yarn spools for knitting machines or the like, comprising a plurality of bars disposed vertically and at an angle to the horizontal, a plurality of spool-engaging members fixed on each of said bars in spaced relation to one another, yarn tensioning means associated with each of said spool engaging members and a yarn guiding and spacing plate below said bars, set at an angle to the horizontal, said plate having a plurality of spaced apertures arranged in rows at an angle to an edge of the plate.

8. Knitting apparatus of the character described comprising, in combination, a needle cylinder having needles thereon, a rotary table arranged about the said cylinder, a wrap finger ring arranged above the hollow of said cylinder, a plurality of wrap fingers arranged on the said ring, and a rack for supporting yarn spools for said fingers arranged over the said ring and comprising an open, hollow, frustoconical structure carrying a plurality of spaced pins parallel to one another and at an angle to the horizontal and a yarn guiding plate arranged adjacent said ring, said plate having a plurality of yarn guiding apertures.

75 9. A yarn spool rack for knitting machines

or the like comprising a pair of spaced apart plates, a plurality of bars circularly arranged, spaced, bars secured between said plates, a plurality of spool supporting pins secured to each of said bars in spaced relation to one another and at an angle to the bars and the horizontal, each of said pins associated with a yarn tensioning member, a plurality of yarn passages in the lower of said plates adapted to permit the passage of yarn from spools supported on the pins and a yarn guiding and spacing plate arranged in operative position and below said perforated plate, said guiding plate having a plurality of spaced individual yarn guiding apertures.

10. In knitting apparatus of the character described, having a wrap finger ring and a plurality of wrap fingers arranged thereon, a rack for supporting individual yarn supplying spools for each of said wrap fingers, comprising a post fixed centrally of said wrap finger ring, a pair of spaced horizontally disposed members fixed to said post, a plurality of bars fixed intermediate said horizontal members, said bars being inclined to the horizontal, a plurality of spool supporting pins secured to each of said posts in spaced horizontal relation to one another, and at an angle to said bar and to the horizontal, the lower of said horizontal members having a plurality of yarn passages and a yarn guiding plate supported below said lower member and at approximately the level of said wrap fingers, said plate having a plurality of spaced yarn guiding apertures arranged in rows disposed at an angle to the radii of the said ring.

11. In a knitting apparatus of the character described, having a wrap finger ring and a plurality of wrap fingers arranged thereon, a rack for supporting individual yarn supplying spools for each of said wrap fingers, comprising a post 35 extending above said wrap finger ring, a pair 40 of spaced horizontally disposed members fixed to said post, a plurality of bars fixed intermediate said horizontal members, said bars being inclined to the horizontal, a plurality of spool supporting pins secured to each of said bars in spaced relation to one another, the lower of said horizontal members having a plurality of yarn passages and a frustoconical yarn guiding plate below said lower member and at approximately the level of said wrap fingers, said plate having a plurality of spaced yarn guiding apertures arranged in rows disposed at an angle to the radii of the said ring.

12. A yarn spool rack for knitting machines having a yarn supply and needles and in which the yarn travels generally in a vertical plane in passing from the supply to the needles, including a plurality of spool supporting members, each of said members being associated with a yarn guiding or tensioning member, said yarn guiding 60

and tensioning members comprising an arm having a forked end, the prongs of said forked end each having a yarn guiding aperture, a resilient member secured on said arm and having a yarn guiding eye, said resilient member being arranged to have said eye disposed opposite the apertures in the prongs of said forked end and adapted to be urged away therefrom, whereby the resilient member urges the yarn in a direction at right angles to the plane in which the yarn travels.

13. In combination with a knitting machine, having a yarn supply and needles of the character described, and in which the yarn travels generally in a vertical plane in passing from the supply to the needles, a yarn tensioning device comprising an arm having a pair of spaced prongs each provided with a yarn guiding aperture, a resilient member secured on said arm and extending intermediate said prongs and having a yarn guiding eye disposed opposite said apertures, said resilient member being free to urge the yarn away from its position intermediate said prongs and opposite said apertures and in a direction at right angles to the plane in which the yarn travels and thereby to have tension applied to the yarn.

14. In combination with a knitting machine, having a yarn supply and needles, of the character described, and in which the yarn travels generally in a vertical plane in passing from the supply to the needles, a yarn tensioning device comprising an arm having a pair of spaced prongs each provided with a yarn guiding aperture, a resilient member secured on said arm and extending to a position intermediate said prongs, said resilient member having a yarn guiding eye to receive the yarn passing through said apertures in said prongs whereby the tensioning device operates by the movement of the resilient member so as to urge the yarn in a direction at right angles to the plane in which the yarn travels.

15. In combination with a knitting machine, having a yarn supply and needles, of the character described, and in which the yarn travels generally in a vertical plane in passing from the supply to the needles, a yarn tensioning device comprising a support for the yarn supply, an arm having a bifurcated end secured to said support, the prongs of said bifurcated end having apertures, a resilient member constituted of a spring wire anchored upon said arm and extending to a point intermediate said apertures, said resilient member having at its end a yarn guiding eye, said resilient member being free to urge the yarn in a direction at right angles to the plane in which the yarn travels, and thereby apply tension to the yarn.

RAYMOND KRETSE
